UNITED STATES PATENT OFFICE.

HARRY K. SMITH, OF HAMILTON, BALTIMORE, MARYLAND.

BAIL-EAR FASTENING FOR CANS.

1,353,080.

Specification of Letters Patent. Patented Sept. 14, 1920.

Application filed March 7, 1919. Serial No. 281,210.

To all whom it may concern:

Be it known that I, HARRY K. SMITH, a citizen of the United States, residing at Hamilton, in the city of Baltimore and State of Maryland, have invented a new and useful Bail-Ear Fastening for Cans, of which the following is a specification.

This invention relates to bail ear fastenings for cans.

10 The object is to provide an ear for ready connection with the bail of a can, pail or bucket of the sheet metal type and which is adapted to be secured to the said can or pail, during the process of manufacture thereof, without the use of solder or rivets.

15 A further object is to provide a bail ear stamped out of sheet metal which is incorporated in the structure of the can by the single operation now required to secure 20 the head to the can body.

A full and complete understanding of the invention may be obtained from a consideration of the following detailed description taken in connection with the accompanying drawing forming a part of this specification, it being understood that while the drawing shows a practical form of the invention, the latter is not confined to strict conformity therewith but may be changed 25 or modified, so long as such changes or modifications mark no material departure from the salient features of the invention, as specifically pointed out in the appended 30 claims.

35 In the drawings, in which like reference characters designate corresponding parts throughout the several figures:—

Figure 1 is a side elevation of the upper portion of a can or pail, partly broken away and having the invention applied thereto.

40 Fig. 2 is a detail perspective view of a portion of a can or pail and showing one of the ears applied thereto and its connection with the bail.

45 Fig. 3 is a detail sectional view of the component parts of a can showing the improved ear in position prior to the crimping operation which secures the same in place.

50 Fig. 4 is a similar view, after the crimping operation and showing the bail in place; and

55 Fig. 5 is a detail perspective view of one of the improved ears.

55 Since the exact structure of the can, pail or bucket proper forms no part of the pres-

ent invention, the improved bail ears being equally applicable to any can or pail of the so-called "sanitary" type, wherein a head is secured to the body of the can by a crimping process, no attempt has been made to illustrate the construction of the body of the can.

There is illustrated the upper portion 1 of a can or pail body having its upper edge initially turned outwardly to form a peripheral flange 2, extending entirely around the body and adapted to be bent into interlocking engagement with the can or pail head during the crimping operation required to secure the latter upon the body.

The can or pail head 3 is provided with a raised annular peripheral gripping portion 5 which, when locked into engagement with the body 1, surrounds a sunken or depressed head having a central filling or emptying opening 6.

The gripping portion of the head is initially provided, around its margin, with a downwardly and inwardly curved, depending flange 8, open toward the center of the head, and of a diameter to freely pass over the marginal edge of the outwardly directed peripheral flange 2 of the body 1 prior to the operation of locking the two members together.

The body and the head, as hereinbefore described, are of the ordinary construction, and it will be readily seen how they may be secured together by the well-known crimping operation practised in this art.

Bail ears are usually secured to the bodies of cans or other receptacles by soldering or riveting the same together, but these methods add materially to the cost of production. The improved bail ears are designed to be secured to the body of the can or pail and to be held thereto by means co-acting with the said flanges 2 and 8 and to be locked therewith during the aforesaid process of fastening the head 1 to the body.

To this end, the ears are stamped from sheet tin or other metal and comprise a plate 9, preferably rounded at its bottom portion, as at 10, and bent transversely to assume a curvature corresponding with the periphery of the body 1. The plate 9 is provided at its upper edge with an outstanding flange 11 of less width than the aforesaid flange 2 of the body 1, and has its central portion pressed outwardly, in the

same direction as the flange 11, to form a boss 12 having its upper wall 13 merging, at an inclination, into the body portion of the plate 9, thus providing an angularly disposed bottom portion or wall 14 extending around the major portion of the boss and serving to strengthen or brace the same. Centrally of the boss there is provided an aperture 15 for the purpose of receiving the 10 hooked end 16 of the bail 17, after the improved ear has been secured to the can body in a manner now explained.

A pair of the ears are placed at diametrically opposite points of the can body 1 with their flanges 11 located directly beneath and bearing against the flange 2 of the body 1, and the plate 9 lying flat against the body. The head 3 is then placed upon the upper end of the said body, when the curved flange 8 will pass freely around the flanges 2 and 11 respectively, as shown in Fig. 3. By a crimping operation in the proper machine, the several flanges are rolled or crimped into interlocking relation, 25 forming an annular outstanding bead as illustrated in Fig. 4 of the drawing, so that the improved ear remains in locked position. The hooked end 16 of the bail 17 may be introduced into the aperture 15 and will 30 remain therein, permitting the necessary swinging action of the bail and preventing any separation of the same from its engagement with the ear.

From the foregoing it will be seen that 35 a simple, cheaply manufactured, and easily applied bail ear has been provided, which by reason of its shape will resist any buckling action due to the weight of the contents of the can body.

40 What is claimed is:—

1. In a device of the class described, the combination with a container having an initially formed annular flange outstanding from its upper edge at substantially right angles to the sides thereof, and a head having a flange fitting over and partly inclosing the outstanding flange, of a bail ear comprising a base plate and a hollow boss projecting from the plate, said boss being provided with means to engage with an end of the bail, said ear also having an outwardly extending flange formed on the upper end of

its base plate, said ear flange fitting against the under side of the aforesaid outstanding flange of the container, the three flanges being interlocked with each other when the flanges are rolled into a bead with the flange of the cover innermost. 55

2. In a device of the class described, the combination with a container having an initially formed annular flange outstanding from its upper edge at substantially right angles to the sides thereof, and a head having a flange fitting over and partly inclosing the outstanding flange, of a bail ear 60 comprising a base plate and a hollow boss projecting from the plate, said boss being provided with means to engage with an end of the bail, said ear also having an outwardly extending flange formed on the upper end of its base plate, said flange fitting against the under side of the aforesaid outstanding flange of the container, the three flanges being interlocked with each other when the flanges are rolled into a bead with 65 the free edge of the cover flange received between said base plate and the flange of the ear, the flange of the container being interposed between the cover flange and the ear flange. 70

3. In a bail ear fastening for metallic containers, the combination with a container having an initially formed outstanding flange at the upper edge thereof and having a head or cover provided with an initially formed downwardly and inwardly curved flange, the flange of the head being wider than the flange of the container and partly inclosing the same, of a bail ear having an initially formed outturned flange on 85 its upper side adapted to be placed against the under side of the body flange and within the curved flange of the head, whereby when the said head flange is crimped or rolled with the flange of the body the flange of the 90 bail becomes interlocked with and between the other two flanges and the ear is held in place on the container without the use of additional fastening means. 95

In testimony that I claim the foregoing 100 as my own, I have hereto affixed my signature.

HARRY K. SMITH.
